ATTORNEY

UNITED STATES PATENT OFFICE

JAMES McINTOSH, OF CLEVELAND HEIGHTS, OHIO

FUEL MIXER FOR INTERNAL-COMBUSTION ENGINES

Application filed May 2, 1928. Serial No. 274,444.

This invention relates to fuel mixers for internal combustion engines and consists in certain improvements in construction thereof and will be hereinafter fully described and 5 pointed out in the claim.

The invention is especially useful in connection with engines where the range of power output is great as in the usual automobile.

10 The primary object of the invention is to provide an improved apparatus for preparing and heating a charge of mixture and thus equalize the fuel value delivered to each combustion space.

15 A further and very important object is the provision of an improved manifold structure embodying means to atomize a charge.

20 A further and important object is to arrange the several essential parts so that there is (what is essential at low speeds and light loads) an increase in the velocity of the flow of mixture at the point of distribution, advantage is taken of the value of a Venturi tube into which there is a nozzle 25 and the constriction and nozzle action is used to speed up the flow and atomize the charge of mixture flowing from the carburetor, the increased velocity at the point of charge division and the action of diverging spirally 30 arranged nozzle jets produce the effect essential to break up the particles of gasoline or other liquids that tend to combine on light loads due to the relatively slow velocities in throttled conditions.

35 With the above mentioned and other ends in view, the invention consists in the novel construction, arrangement and combination of parts, hereinafter described and illustrated in the accompanying drawings, in 40 which:

Fig. 1 is a section of an intake pipe between a carburetor and engine cylinder, the section indicating the features involved.

45 Fig. 2 is a front sectional elevation of a conventional inlet manifold for delivering a charge of mixture from a carburetor to a multiple cylinder engine where there is shown the preferred embodiment of my invention and the details to control its action.

50 Figs. 3 and 4 are details of the valve in

different positions. Similar numerals of reference designate like parts of either figure.

In Fig. 1, numeral 1 indicates an inlet of mixture from a carburetor, 2 an outlet attached to a cylinder, 3 an air cock, 4 a tube nozzle terminating with a bulb shape, 5 a series of openings or slots spirally located, and 6 a constricted area. Arrows indicate direction of flow.

In Fig. 2, 1 is the inlet for mixture from a carburetor, 2 outlet or discharge openings for mixture to the cylinders, 3^a a control cock in position, 4 the tube nozzle, 5 a series of openings arranged spirally and forming the outlets from the nozzle. Figs. 2, 3 and 4 show the three way cock 3^a in the different positions used to produce the several results, and 3^b indicates an opening to admit gases and vapors, and 3^c indicates an opening from any 70 source of pressure supply to admit pressure, exhaust gases or air.

Fig. 2 indicates the position of the cock where the flow of exhaust gases is in a straight line passing from 3^c to 3^d and in doing so 75 produces an injector effect and depression at 3^b.

Fig. 3 indicates the side opening free to deliver fluids from 3^b to 3^d while 3^c is shut off and inoperative.

Fig. 4 indicates the direct flow of pressure from 3^c to 3^d with the side opening 3^b shut off.

It will be evident that the relation of the key of the cock may be any position intermediate of that indicated even to a shut position when the nozzle flow is entirely shut off.

The structure shown in Fig. 1 is used to atomize a charge and regulate in strength to attain the best economy for any given mixture.

That shown in Fig. 2 is used to accomplish several valuable results and more particularly when the engine is operating at less than full power.

It will be evident that under throttled control this device is more active due to the depression above the throttle and in that respect it may be said to be controlled by the throttle opening used which makes it practically automatic in action and the result is 100

more potent where it is most essential, that is when the velocity of the flow of mixture in the manifold is reduced the action of the nozzle is increased to compensate for the losses due to the failure of a mixture to retain a homogeneous composition.

I claim:

The combination with a fuel mixture pipe having a constriction therein, of a nozzle projecting into the passage within said constriction with outlets directed against the flow of mixture in the pipe, said nozzle having gas and air inlets, and a valve controlling said inlets to vary the pressure of the gas and air supply thereto the nozzle having a bulb at the end with angular slots therein.

In testimony whereof, I do affix my signature.

JAMES McINTOSH.
